UNITED STATES PATENT OFFICE.

EMANUEL B. CUMP, OF COLUMBUS, OHIO.

IMPROVEMENT IN LIFTING-JACKS.

Specification forming part of Letters Patent No. 146,235, dated January 6, 1874; application filed December 2, 1873.

To all whom it may concern:

Be it known that I, EMANUEL B. CUMP, of Columbus, in the county of Franklin and State of Ohio, have invented an Improvement in Lifting-Jacks, of which the following is a specification:

This invention relates to lifting-jacks in which the raising of the sliding prop is effected by a cam-shaped head on the lifting-lever. My improvement consists in pivoting the lifting-lever on the sliding prop in such a manner that its cam-shaped head will bear upon the top of the standard.

In making this change in the ordinary arrangement of the parts, two objects were had in view—first, the obtainment of a long range of motion of the lever, by elevating its fulcrum without unduly elongating the standard and prop, to enable me to use, for lifting the prop a given distance, a cam of less abruptness and consequently greater power; and, secondly, the rising of the lever bodily as it is turned down on its fulcrum, for the greater convenience of operating it.

In the annexed drawings, Figure 1 is a perspective view of my improved lifting-jack. Fig. 2 is a sectional elevation thereof.

The same letters of reference are used in both figures in the designation of identical parts.

The standard A is embraced by the hollow sliding prop B, which carries near its upper end the lifting-lever C, permanently pivoted to it in such relation to the standard that, when the prop rests upon the base of the latter, the cam-shaped head of the lever, bearing upon its top, will throw the lever into a nearly-vertical position, as shown in Fig. 2. The inclination of the cam-surface of the head C' is made very gradual, permitting of the use of a lever of medium length to exert the requisite amount of power with ease; and the lever, being pivoted at an elevated point, can be moved through

an arc of about one hundred and eighty degrees, so that, notwithstanding the gradual slope of the cam-head, the required lift can be obtained.

It is obvious that as the lever rises with the sliding prop it may still be moved through an arc of the length specified, even though its length should somewhat exceed the distance between its fulcrum, when at rest, and the base of the standard. Another important advantage is derived from the bodily rising of the lever with the sliding prop, and that consists of the greater ease with which it may be operated by reason of remaining, through the greater part of its path, at elevation most convenient to the operator in manipulating it.

The fulcrum-pin c projects some distance through the sliding prop on one side, and carries on its overhung end a hook-bar, D, provided with a vertical series of holes, d, which permit of its ready vertical adjustment. This hook-bar may be hung upon or connected to the prop directly, if preferred. It is of great convenience in lifting panels of rail fences and other objects which cannot readily be operated upon in the usual manner, but afford facilities for the use of a hook. The top of the prop is "stepped" in the usual manner.

What I claim as my invention, and desire to secure by Letters Patent, is—

The solid standard A and hollow sliding prop B, in combination with the lifting-lever C C', when the latter is pivoted at an elevated point to the prop, bearing with its cam-shaped head upon the standard, substantially as and for the purpose specified.

In testimony whereof I have signed my name to this specification in the presence of two subscribing witnesses.

EMANUEL B. CUMP.
